UNITED STATES PATENT OFFICE.

TEODORO LARREY AND LUIS GODARD, OF MEXICO, MEXICO.

STEAM-BOILER INSTALLATION.

Application filed May 1, 1924. Serial No. 710,435.

To all whom it may concern:

Be it known that we, TEODORO LARREY and LUIS GODARD, citizens of the United Mexican States, residing at Mexico city, Federal District, Mexico, have invented certain new and useful Improvements in Steam-Boiler Installations, of which the following is a specification.

This invention relates to superheating and evaporating units combined with a heat-distributing deflector, of which the following is a complete description.

Different kinds of superheaters for locomotive and other boilers are known, being generally formed by tubes disposed in every flue in order to conduct saturated steam taken from a multiple feeding head to a multiple collector head of superheated steam, but all these multiples offer a serious inconvenience because owing to their reduced volume it is difficult to obtain tight unions, and furthermore the reduced space does not permit of an individual tightening of each tube to the said multiples. Consequently, the tightening is done in series of tubes which in itself constitutes a problem, because a still greater exactness at their faces of union is required and also a mutual correlation between all the tubes of the tightening piece.

In two inch flues of existing boilers no group of steam conducting tubes could fit. In such boilers it has not been possible to install steam superheating tubes, because no more than one single tube could fit within a flue of two inch diameter, wherefore it would have to project into the fire place and return by another flue.

No tube could resist the high temperature in the fire place, and if the tubes were made shorter than the flues, then no circulation of steam could be obtained. It has therefore been necessary to change the flues, substituting others of larger diameter whenever a locomotive boiler is adapted for a superheating installation, and we intend to avoid such changes of flues by using single pipes, either straight or curved disposed within the flues eccentrically or concentrically, each tube carrying in its interior a flat dividing bar which will permit the passage of steam from one half of the tube to the other, the steam circulating by passing around the end of the flat bar and then continuing through the other half of the tube in the opposite direction; all said tubes being connected to a heat

distributing deflector. The deflector is divided into two parallel chambers for this particular use, one in order to distribute saturated steam and the other to receive the superheated steam collected from all the pipes thereafter conducting it to the cylinders by the steam pipe, when the apparatus is working as a superheater, or to the boiler at a higher level than that of the water in the boiler when it works as an evaporator.

This invention also refers to a special construction of stopper providing entrance to and outlet from the tubes as well as to the heat distributing deflector.

Fig. 1 is a longitudinal vertical cross section of a locomotive equipped with a heat distributing deflector and our superheating units.

Fig. 2 is an end elevation of the smoke box showing the deflector and the superheating units.

Fig. 3 is a transverse cross section of a heat distributing deflector having one of our superheating units applied.

Fig. 4 is a horizontal cross section of a superheating unit mounted in its flue and a fraction of the deflector.

Fig. 5 is a transverse cross section of a flue equipped with a superheating unit.

Fig. 6 is a longitudinal vertical cross section of a locomotive with deflector and evaporating units.

Fig. 7 is an end elevation of the smoke box showing the deflector and evaporating units.

Fig. 8 is a transverse cross section of a flue with a straight pipe eccentrically disposed in same.

Fig. 9 is a transverse cross section of a flue with a curved pipe.

Fig. 10 is a transverse cross section of an oval pipe with a channel iron soldered to it.

Fig. 11 is a transverse cross section of a rolled superheating or evaporating unit.

(1) is a smoke box of a locomotive, the flue sheet (2) of which carries the common flues (3) of two inch diameter, while (4) is a saturated steam pipe which is joined to a T connection (5), the arms (6) of which are connected to the corresponding members of the heat distributing deflector (7). The latter is composed of the exterior plates (8) and (9) between which is placed the intermediate plate (10), which at its top prolongs into a flange (11) like the exterior plate (8). The exterior plate (9) is soldered against the said flange (11) on the middle plate

(10) and is also soldered along its edge to the small flange of the exterior plate (8). Two separate chambers (11) and (12), one a distributing chamber, and the other a receiving chamber, are thus formed.

In the lower part of the deflector the middle plate (10) is recessed in front of the outlet (14) which is provided with a flange so that it may be connected with the flange 10 (15) of the pipe (16), conducting superheated steam towards the cylinder from that half of the deflector.

The plates (8), (9) and (10) are maintained apart by the tubular spacing pieces 15 (17) through which pass the stay bolts (18).

In each of the flues (3) that offer facilities for superheating due to their position, we dispose a tube (19), each said tube having a solid somewhat pointed tip (20) welded 20 on to the extreme end. Now, the other end of said tube (19) is threaded and connected into the bored stopper (21) and finally soldered at (22).

The bored stopper (21) has an inlet perforation (23) and an outlet perforation (24), each communicating with the corresponding chamber (12) and (13).

The conical stopper (21) is threaded on its solid end (25) on which is placed a copper packing washer (26) held by the nut (27), the opposite end being formed with a retaining shoulder (28) for engagement with its packing ring (29) of copper.

Before the tube (19) is connected to the 35 conical bored stopper, a flat bar (30) is inserted after having been edge-planed so that it will properly adjust itself along the diameter within the tube; then it is brought up against the solid end (25); while the opposite end must be spaced sufficiently from the tip (20) to enable the volume of steam to pass from the upper part of the pipe to its lower part.

We have shown three tubes of different 45 cross section, viz a circular tube, an oval tube, and a third tube which was originally circular but afterwards rolled, so that both sides of the tube at the edges of the flat bar are pressed together, thus maintaining in the 50 middle of the tube the flat bar (30) which divides it into two equal parts or sections. When the tubes have been provided with their division bars (30), they can be placed within the flues, either concentrically or eccentrically, or the end near the fireplace may be offset (Fig. 9).

At spaced intervals every tube carries rings (31) having radial feet (32), although such supports are not necessary. The end 60 (25) of the conical stopper is grooved at (33) to indicate the position of the division bar (30).

In Figs. 6 and 7 are seen some modifications, by which a heat distributing deflector 65 with connected tubes (19) may operate as an

evaporating device, the only difference consisting, however, in the way of disposing the bored stoppers (21) because the perforation (23) should in this instance open downward and the perforation (24) should open upward. In certain cases the tubes (19) of course may be disposed so that the dividing walls (30) stand upon their edge either vertically or inclined.

In the construction of Figs. 6 and 7 the 75 pipes (34) which connect the inlet and outlet pipes are required for each half of the deflector. Here the entrance pipe (35) of each half is connected to the flue sheet while the opposite end is connected to the chamber 80 (12) of the deflector. An outlet pipe (36) extends through the flue sheet (2) above the pipe (35), and the other end of the pipe (36) is connected with the chamber (13) of the deflector. Both parts of the deflector are 85 joined by angle irons (37) and supported by feet (38) and stay bolts (39).

Having thus described our invention what we claim is:

1. A superheating unit, comprising a tube 90 closed at its inner end and having its outer end open and externally threaded; a flat division bar disposed axially within the tube and dividing the interior thereof into two compartments, said bar terminating at its inner end short of the closed end of the tube to permit communication at that end between said compartments, and projecting at its outer end through the open end of the tube; and a stopper mounted on the threaded end of the tube and having an axial bore which registers with the tube bore and which receives the projecting portion of the bar so as to provide extensions of the tube compartments, the free end of said projecting portion abutting against the end wall of the stopper bore to prevent communication between the compartment extensions; said stopper being formed with a pair of openings communicating directly 105 with said extensions.

2. A superheating unit, according to claim 1, in which the closed inner end of the tube is pointed, and in which the stopper is of gradually-decreasing diameter from its inner 110 to its outer end.

3. A superheating unit, according to claim 1, in which the stopper is of gradually-decreasing diameter from its inner to its outer end and is formed adjacent its inner end with a circumferential centering shoulder, the outer end of the stopper being reduced to form a similar shoulder and being externally threaded.

4. The combination, with a deflector embodying steam receiving and delivering chambers, of a superheating unit comprising a tube closed at its inner end and open at its outer end; a stopper fitted on the open end of the tube and having a bore which forms 125

- a continuation of the tube bore; and means within the tube and stopper bores dividing the interior thereof into two compartments, said means abutting directly against the inner end of the stopper bore but terminating short of the inner end of the tube bore so as to permit communication between said compartments at the latter end only; said stopper being formed with a pair of lateral openings which provide communication between one compartment and the steam delivering chamber and between the other compartment and the steam receiving chamber.
- 5 5. A steam installation, according to claim 4, in which the steam delivering and receiving chambers are disposed vertically and face to face, and in which the openings in the stopper are disposed in different vertical planes.
- 10 6. The combination, with a deflector embodying steam receiving and delivering chambers, of a superheating unit comprising a tube closed at its inner end and having its outer end open and externally threaded; a flat division bar disposed axially within the tube and dividing the interior thereof into two compartments, said bar terminating at its inner end short of the closed end of the tube to permit communication at that end between said compartments, and projecting at its outer end through the open end of the tube; and a stopper mounted on the threaded end of the tube and having an axial bore
- 15 which registers with the tube bore and which receives the projecting portion of the bar so as to provide extensions of the tube compartments, the free end of said projecting portion abutting against the end wall
- 20 of the stopper bore to prevent communication between the compartment extensions; said stopper being formed with a pair of lateral openings which provide communication between one compartment and the steam delivering chamber and between the other compartment and the steam receiving chamber.
- 25 7. The combination, with a deflector embodying parallel steam receiving and delivering chambers disposed face to face, of a multiplicity of superheating units each comprising a tube closed at its inner end and open at its outer end; a stopper fitted on the open end of each tube and having a bore
- 30 which forms a continuation of the tube bore; and means within the bores of each tube and its related stopper to divide the interior thereof into two compartments, said means abutting directly against the inner end of the stopper bore but terminating short of the inner end of the tube bore so as to permit communication between said compartments at the latter end only; each stopper being formed with a pair of lateral openings which are disposed in different vertical planes, one opening of each pair providing communication between one compartment of the corresponding tube and the steam delivering chamber and the other opening of each pair providing communication between the other compartment of the corresponding tube and the steam receiving chamber, thereby to enable steam to be fed from the delivering chamber to all the tubes simultaneously, and from all the tubes simultaneously to the receiving chamber.
- 35 In testimony whereof we have affixed our signatures.
